(57) **CLAIM**

The ornamental design for a rotating and reflective light as shown and described.

DESCRIPTION

FIG. 1 is a perspective view of a rotating and reflective light showing my design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines of the rotating and reflective light are for the purpose of illustrating portions of the article that form no part of the claimed design.
